UNITED STATES PATENT OFFICE.

WILLIAM H. SWIGART, OF LUCAS, OHIO.

ROAD-BED CONSTRUCTION FOR RAILWAYS.

SPECIFICATION forming part of Letters Patent No. 755,810, dated March 29, 1904.

Application filed December 29, 1903. Serial No. 187,033. (No model.)

To all whom it may concern:

Be it known that I, WILLIAM H. SWIGART, a citizen of the United States, residing at Lucas, in the county of Richland and State of Ohio, have invented certain new and useful Improvements in Road-Bed Construction for Railways; and I do hereby declare the following to be a full, clear, and exact description of the invention, such as will enable others skilled in the art to which it appertains to make and use the same.

My invention relates to road-bed construction for railways; and it consists of certain novel features of construction and combination of parts, as will be hereinafter clearly set forth.

The prime object of my invention is to provide a road-bed which will be found solid and reliable in resisting the strain placed thereon incident to the passing of heavy trains and to freezing and thawing.

Further objects and advantages will be hereinafter made apparent from the following specification considered in connection with the accompanying drawings, which are made a part of this application, and in which—

Figure 1 illustrates a perspective view of a section of road-bed and showing a portion of the track-rails secured thereon. Fig. 2 is a perspective view of one of the transversely-disposed stays or tying-beams. Fig. 3 is a detail view showing a section of Fig. 4 on line 3 3. Fig. 4 is a transverse section of a track-way or road-bed. Fig. 5 is a sectional view of Fig. 4, taken on line 5 5.

For convenience in referring to the various elements of my invention and coöperating accessories numerals will be employed, the same numeral applying to a similar part throughout the several views.

Referring to the numerals on the drawings, 1 indicates the main or supporting beams, which are disposed beneath, and therefore longitudinal with, the track-rails 2, which latter are made in the usual or any preferred style to adapt them for heavy railway traffic or to meet the requirements of street-railways. It therefore becomes desirable and important to truly aline the main or supporting beams 1 in their respective operative positions and

securely lock the same, whereby they will be held against all lateral movement incident to the heavy strain placed thereon by passing trains, and more particularly to anchor them in place upon curves which may be made in 55 the track, and with this purpose in view I provide a plurality of interlocking members or cross-beams 3, designed to coöperate with both of the supporting-beams 1, preferably in a manner hereinafter particularly set forth. 60

The cross-sections or bracing-beams 3 are preferably made of that form of angle-iron shaped like the letter T in cross-section, and I therefore form at proper intervals throughout the length of the supporting-beams 1 a 65 plurality of transversely-disposed recesses of sufficient depth to receive the downwardly-projecting rib 4, it being understood that the meeting ends of two of said beams 1 may be cut away to receive said downwardly-extending rib or flange 4 between them, or said ends may be properly spaced, if preferred, to receive said rib. I also shape the contiguous part of the supporting-beams 3 so that the ends of the stay members 3 may be let down 70 75 so that the upper surface thereof will be flush with the upper surface of said beams, thus enabling the track-rails 2 to rest squarely upon a continuous supporting-surface, and thus attaining the most desirable results, inasmuch as the road-bed or support thus provided for the track-rails will be uniform or solid throughout the length thereof.

In some instances suitable apertures 5 are provided in the interlocking members 3, said 85 apertures being located at a proper point to coincide with the desired position occupied by the anchoring-spikes 6 for the track-rails 2, the said anchoring-spikes being entered in and driven through the apertures 5 into a contiguous part of the beam 1, thereby insuring that not only the track-rail will be reliably anchored in its operative position, but that the beam 1 and staying members 3 shall be secured against relative movement by said anchoring-spikes. I also in some instances provide the struck-up lips 7, formed integral from the edges of the staying members 3, at a proper point to snugly receive between them the edges of the base of the track-rail, suit- 90 95 100

able apertures 8 being formed in the staying member to permit proper anchoring - pins to be driven therethrough into a contiguous part of the beams 1, whereby said staying members 5 and said beams will be held against relative movement and insuring that the beams 1 will be reliably secured in place and prevented from spreading.

If preferred, only an occasional one of the 10 staying members 3 may be provided with the struck-up lips 7, the others being formed substantially as shown in Fig. 1, though I reserve the right to adopt either construction which in practice I may find most desirable.

15 If preferred, the recesses which are formed in the beam - sections 1 may be made in the form illustrated in Fig. 4, so as to receive the beveled end 9 of the rib 4, this form of recess rendering it unnecessary to cut the recess sufficiently deep to seriously weaken the capacity of the beam for supporting the load placed thereon.

20 In some instances the extreme end of the staying member may be bent downward at right angles to form the terminal 10, it being understood that a suitable recess shall be formed in a contiguous part of the beam 1 to receive said terminal 10, whereby said beam will be held against all lateral movement.

25 30 It will thus be seen that I have provided very reliably efficient means for securely supporting the track-rails in their operative positions and also holding said rails against spreading, and since the beams 1 may be supported 35 upon a solid concrete bed or other preferred form of support a road - bed of permanent

character is provided at a comparatively small cost.

While I have described the preferred combination and construction of parts deemed necessary in materializing my invention, I desire to comprehend all substitutes and equivalents which may be considered as falling fairly within the scope thereof.

Believing that the advantages and manner 45 of constructing my improved road - bed and rail-securing appliance have thus been made clearly apparent, further description is deemed unnecessary.

What I claim as new, and desire to secure 50 by Letters Patent, is—

The herein-described road-bed comprising the main or supporting beams 1 sustained in position by a suitable bed of concrete or the like, in combination with a plurality of staying members or cross-sections 3 having a depending flange or rib 4, said flange being adapted to fit into suitable recesses provided in a contiguous part of said supporting-beams and means co-operating with said staying members 55 to secure the track-rails thereon and lock said staying members and supporting-beams in operative union, all combined substantially as specified and for the purpose set forth.

In testimony whereof I have signed my name 60 to this specification in the presence of two subscribing witnesses.

WILLIAM H. SWIGART.
